UNITED STATES PATENT OFFICE.

AUGUSTUS F. LETSON, OF BUFFALO, NEW YORK, ASSIGNOR, BY MESNE ASSIGNMENTS, TO FRANK ALTON FOX, OF SAME PLACE.

AUTOMATIC FIRE-EXTINGUISHER.

SPECIFICATION forming part of Letters Patent No. 357,719, dated February 15, 1887.

Application filed December 9, 1885. Serial No. 185,114. (No model.)

To all whom it may concern:

Be it known that I, AUGUSTUS F. LETSON, a citizen of the United States, residing in Buffalo, in the county of Erie and State of New York, have invented certain new and useful Improvements in Automatic Fire-Extinguishers, of which the following is a specification.

The object of my invention is to produce a portable fire-extinguisher adapted to act automatically when thrown into a fire; and it consists of a strong glass vessel for holding a liquid alkaline solution and a thin vial-shaped vessel having a bell-shaped mouth for holding a suitable acid salt, also a small charge of gunpowder separated from the acid salt by means of cotton or other similar substance, together with a fuse protected from the acid salt by paper or other suitable material, and a packing-ring to prevent the cement used for sealing the whole together from dropping into the glass vessel during the operation of sealing, all of which will be fully and clearly herein-after shown, described, and claimed by reference to the accompanying drawings, in which—

Figure 1 is a side elevation, a portion being broken away so as to show a part of the interior of the vial for holding the acid salt, powder, fuse, &c., and also for showing the manner of sealing the vial and the whole together. Fig. 2 is a top view of the device. Fig. 3 is a detached perspective view of the thin glass vial for holding the acid salt, explosive material, &c.; and Fig. 4 represents a face view of the elastic packing before being put onto the vial.

In said drawings, 1 represents the glass vessel for holding the alkaline solution. It is made strong, so as not to be easily broken, and is provided with a neck, 2, for holding the vessel containing the acid, explosive material, and the packing.

3 represents the vial for holding the acid. It is provided with a flaring mouth, 4, so that the cement for sealing it may be easily poured in while in a hot or in a molten state. Into this vial is placed first a suitable acid, not in the liquid form, but in the form of dry crystals, so as not to injure the powder or other explosive material. I have found that oxalic acid answers the purpose, and therefore fill

the vial 3 partly full of oxalic acid, 5, (see Fig. 3,) and then a layer of cotton or other similar material, 6. Upon this layer of cotton I place a small charge of gunpowder, 7, and then insert a fuse, 8, into the powder, and a layer of 55 cotton, 9, or other similar packing material to prevent the cement when poured in to seal it from getting to the powder. I have found common sealing-wax to answer a good purpose.

The fuse is covered with paper, 10, as far as it enters the glass-case 1 and the vial as a protection while sealing it.

A packing-ring, 11, of some suitable material, (rubber, for instance,) is placed on the 65 glass vial before entering it into the glass vessel 1. This ring acts as a packing and forms a tight joint, so that when the cement 12 (see Fig. 1) is poured in it will prevent it from running through into the liquid alkaline solution 13.

The sealing of the vial in place and the mouth of vessel 1, which is provided with a groove, 14, so as to hold the cement firmly, as shown in Fig. 1, completes the device ready 75 for use.

The charge of gunpowder 7, it will be noticed, is not large enough to burst the glass vessel 1, but is just large enough to shatter the glass vial containing the acid crystals, and 80 when it comes in contact with fire so that the fuse is ignited and the explosion takes place; the vial is separated from its connection near the top and thrown with such force against the bottom of the vessel 1, that it is broken into 85 fragments, and the acid crystals are scattered through the alkaline solution, thereby generating a large quantity of carbonic-acid gas, thereby instantly bursting the vessel 1 and liberating the gas onto the fire and putting it out. 90 By this means a much larger quantity of carbonic-acid gas is liberated in a given time than could be when the acid and alkali are both in the liquid form.

I claim as my invention—

1. An automatic fire-extinguisher consisting of a glass vessel for holding an alkaline solution, a thin glass vessel having a charge of acid in the crystallized form, a small charge of explosive material having a portion of pack-

ing material on each side to separate it from the acid and cement, and a fuse communicating with the explosive material, the whole being securely connected together, substantially as and for the purposes described.

2. In an automatic fire-extinguisher, the combination of an outer shell, 1, for holding the alkaline solution, and an acid and explosive material vessel, 3, having a fuse, and a

packing-ring, 11, adapted to prevent the cementing material from getting into the outer shell while filling the neck 2 with cement, and securing the whole together.

AUGUSTUS F. LETSON.
